UNITED STATES PATENT OFFICE.

PHILIP J. HAAS, OF OMAHA, NEBRASKA.

POULTRY BEHEADER.

Application filed April 9, 1923. Serial No. 630,772.

To all whom it may concern:

Be it known that I, PHILIP J. HAAS, a citizen of the United States, and a resident of Omaha, in the county of Douglas and State of Nebraska, have invented certain new and useful Improvements in Poultry Beheaders, of which the following is a specification.

My invention relates to devices for decapitating poultry for domestic use, and it is the object thereof to provide a simple, efficient and inexpensive device, by the use of which an unskilled or timid person may effect the decapitation of poultry easily, quickly and humanely.

15 In the accompanying drawings Fig. 1 is a front view of a mechanism embodying my invention, Fig. 2 is a vertical transverse section of the same on the line 2—2 of Fig. 1, and Fig. 3 is a horizontal section on the line 20 3—3 of Fig. 1.

In the illustrated structure I provide a U-shaped main frame comprising vertical legs 4 and an arched cross-piece 5 connecting the upper ends of said legs. On the outer 25 sides of the legs at the lower ends thereof are lugs 6 which extend between the forked ends of foot-pieces 7, the latter being fixedly secured by means of screws 8 to a suitable base-member, such as a wooden post 9. At 30 one side a pivotal connection of the lug 6 to the foot-piece is formed by a rivet 10, and at the other side a detachable connection between the lug and foot-piece is formed by a small bolt 11. Removal of the bolt 11 enables the frame to be swung about the axis 35 of the rivet 10 to an approximately horizontal position, for a purpose which will presently appear. In the flat adjacent sides of the legs 4 are two pairs of vertical grooves 40 which form guideways for the blade 12 and a horizontal neck-bar or holder 13. To the upper edge of the blade 12 is connected a tubular stem 14 which extends slidably through an opening therefor in the arched 45 cross-piece 5, the connection of said stem and blade being effected as follows: Near the lower end of the stem one side thereof is cut away to form an offset or shoulder equal to the thickness of the blade, and the flattened or cut away side of the stem is held 50 against the side of the blade by means of a U-shaped clip 15 which extends around the stem and has the ends thereof secured to the blade by rivets 16. The upper edge of the 55 blade rests against the shoulder on the stem, which extends out flush with the outer side

of the blade, as best shown in Fig. 2. In the side of the stem adjoining the clip there is a small recess or countersink, and the adjacent portion of the clip is driven or swaged 60 into said recess to form a projection 17 which interlocks the clip and stem and prevents relative vertical movement thereof. A cap 18 is screwed upon the upper end of the tubular stem, and a coil spring 19 is disposed around the stem between the lower end of said cap and the upper side of the frame cross-piece 5, said spring normally holding the stem and blade in the raised position shown. The lower edge of the 70 blade is sharpened, as indicated in Fig. 2, and the blade may be moved downwardly to bring said sharpened edge into engagement with the base member 9. A cylindrical stem or rod 20 is fixedly connected with the 75 center of the neck-bar or holder 13, said rod being axially alined with the stem 14 and extending slidably into the lower portion thereof. A small coil spring 21 is disposed within the tubular stem between the upper 80 end of the rod 20 and the cap 18, said spring pressing downwardly upon the rod and tending to hold the neck-bar in the lower portion of the guide-grooves therefor in the frame-legs 4.

In the use of the device the same is mounted upon a substantial base, such as a post or chopping-block, at a convenient height. The fowl to be beheaded is held by the legs with one hand, the neck-bar 13 is 90 lifted sufficiently to enable the head of the fowl to be passed beneath the bar, and the bar is then lowered onto the neck, being pressed lightly thereon by the spring 21, so that withdrawal of the head is prevented. 95 Then, by a quick, sharp blow of a mallet, hammer or the like upon the cap 18, the stem 14 and blade 12 are forced downwardly and the sharpened edge of the blade 12 instantly severs the neck of the fowl.

By removal of the bolt 11 and swinging of the frame about the rivet 10 to the horizontal position above mentioned, the neck-bar and rod 20 may be removed from the frame, and by then unscrewing the cap 18 from the 105 end of the tubular stem 14 the latter may be withdrawn from the frame, together with the blade 12, for convenience in sharpening the blade, or for storing the same in a dry place to prevent rusting thereof, 110 should the frame be permanently mounted in an outdoor or exposed location.

Now, having described my invention, what I claim and desire to secure by Letters Patent is:

1. In a device of the class described, an inverted U-shaped frame having vertical legs provided in their adjacent sides with guide-grooves, a blade movable vertically in said grooves, a tubular stem secured to said blade, a neck-bar arranged to move parallel with and adjacent to said blade, a rod extending from said neck-bar and fitting slidably within said tubular stem, and a spring inclosed by said stem and pressing upon the end of said rod.
- 15 2. In a device of the class described, a frame having spaced vertical legs provided in their adjacent sides with guideways, a blade slideable in said guideways, a stem secured to said blade and extending slidably through a portion of the frame, a cap removably secured on said stem, a spring disposed around the stem between the cap and

frame and normally holding the stem and blade in a raised position, foot-pieces secured to a base, and means for pivotally connecting one of the frame-legs to one of the foot-pieces and detachably connecting the other leg to the other foot-piece.

25 3. In a device of the class described, a frame having spaced vertical legs and a connecting cross-piece between the upper portions of said legs, a blade guided for vertical movement between said legs, a base member to which the lower ends of said legs are connected, said base-member extending transversely between the legs to form a block for coaction with the sharpened lower edge of the blade, a stem secured to the blade and extending therefrom upwardly through the cross-piece of the frame, and a spring associated with said stem for holding the blade normally in a raised position.

30 35 40 PHILIP J. HAAS.
